Letter's Patent No. 2465. Dated Sept 25, 1864.

Design for a Candy Piece.

Illustrated referred to in the said Letter's Patent and making part of the same.

Scall where it may concern:

Best known to the undersigned of the City of Philadelphia and State of Pennsylvania have originated and designed a new article for leading, one of which the following is a full and exact description, reference being had to the accompanying photograph, making part of this Specification.

The design relates to that class of figures, which are cast hollow of transparent or opaque candy, and are extensively used as toys for mounting Christmas trees etc. They are made by pouring the heated liquid candy into a metallic mold, after that portion of the candy which comes in contact with the mold has crystallized and hardened to form a shell of sufficient thickness, the inner, yet liquid portion is poured out again and the hollow casting is then removed from the mold, which to this end is arranged to separate in two or more parts.

The figure represents an Elephant, its posture and detailed configuration being fully represented in the annexed photograph.

What I claim as my invention and desire to secure by Letter's Patent is

The Design for a candy figure herein set forth.

Theodore Berger,
